HOISTING DEVICE

Albert L. Stone, Redondo Beach, Calif., assignor, by mesne assignments, to Standard Oil Development Company, Elizabeth, N. J., a corporation of Delaware

Application December 28, 1949, Serial No. 135,364

4 Claims. (Cl. 254—93)

1

My invention relates to a hoisting device. More particularly, my invention relates to a hoisting device which employs a hydraulic cylinder and a sealed flexible piston rod.

In many operations it becomes necessary to raise or to lower a load. For example, in the drilling of boreholes by the rotary drilling method the drill pipe, casing, and various gear must be raised and lowered within the derrick above the derrick floor. This hoisting is conventionally accomplished by means of a draw works driven by a draw works engine. The draw works and its appurtenant equipment occupy considerable space on the derrick floor and on the ground in vicinity of the derrick which could be used more efficiently for other purposes.

The present invention contemplates the employment of at least one hydraulic cylinder having a piston mechanically connected to a flexible piston rod for performing the function normally employed by the conventional draw works, draw works engine and subsidiary equipment. While prior art devices of this general type possessed certain advantages for the suspension of loads, they also possessed certain serious disadvantages. The chief advantage in the employment of a flexible piston rod in devices of this type rather than a rigid piston rod resides in the fact that the length of the piston stroke is approximately half of that required when a rigid piston rod is employed. On the other hand, prior art devices of this type employing a flexible piston rod have not utilized a satisfactory means for packing around the flexible piston rod so as to provide a fluid-tight seal between the rod and the piston rod end of the cylinder. Failure to provide a satisfactory seal at this point has effectively prevented widespread commercial adoption of this type of construction in a lifting device.

Other attempts to avoid the past difficulties encountered when employing flexible piston rods while at the same time avoiding the double length inherent in the use of a rigid piston rod have involved the employment of various telescoping means. The telescoping means employed in some of these devices is similar in principle to the telescoping means employed in hydraulic jacks of conventional design. The obvious difficulty with devices employing such a telescoping means resides in the necessity for providing a multiplicity of fluid-tight seals between the various telescoping elements.

It is an object of my invention to provide a hoisting device which is capable of hoisting a

load approximately the same distance as the length of the stroke of the hydraulic piston used to accomplish the lifting of the load. It is further an object of my invention to provide a hydraulic hoisting device which utilizes a flexible piston rod provided with suitable means for sealing the flexible rod against the passage of a hydraulic fluid. It is a further object of my invention to provide a hydraulic hoisting mechanism which utilizes a flexible piston rod but which requires no telescoping means.

The objects and the advantages of my invention will be readily comprehended from the detailed description of the accompanying drawings wherein:

Fig. 1 is an elevation, partially in cross section, of one embodiment of my invention;

Fig. 2 is a top view of the embodiment shown in Fig. 1;

Fig. 3 is a perspective view of a portion of the embodiment shown in Fig. 1;

Fig. 4 is an elevation, partly in cross section, of a modification of the embodiment shown in Figs. 1, 2, and 3;

Fig. 5 is a detailed showing of a portion of the device of Fig. 4;

Fig. 6 is an elevation, partly in cross section, of another embodiment of my invention;

Fig. 7 is a top view of the embodiment shown in Fig. 6; and

Fig. 8 is an elevation, partly in cross section, of a modification of the embodiments shown in Figs. 1 to 7.

In the drawing like numerals refer to like parts throughout. For the sake of convenience and clarity, the embodiment shown in Fig. 1 will be first described.

Referring to Fig. 1, 10 designates a supporting structure, such as a derrick, on which the device of my invention may be mounted. Numeral 11 designates a transverse member forming a part of the upper portion of supporting structure 10. Upright journaling members 12 are affixed to member 11, members 12 being adapted to receive and support axle 14 for rotation about its axis. Sheave 15 is mounted on axle 14 for rotation therewith. Upright journaling members 13 and upright journaling members 15 are also affixed to member 11, journaling members 13 being adapted to support axle 16 for rotation about its axis and journaling members 15 being adapted to support axle 17 for rotation about its axis. Guide wheel 18 is mounted on axle 16 for rotation therewith and reel 19 is mounted on axle 17 for rotation therewith.

Hydraulic cylinder housing 20 defining cylindrical chamber 23 is supported in an upright position from supporting member 10 and may suitably be affixed to transverse member 11 by bolts 24. Hydraulic cylinder housing 20 is mounted beneath the outer periphery 25 of sheave 15 and the outer periphery 26 of guide wheel 18. Hydraulic cylinder housing 20 is so arranged that the longitudinal axis of cylindrical chamber 23 is substantially tangential to the outer periphery 25 of sheave 15 and to the outer periphery 26 of guide wheel 18. Upper end 27 of hydraulic cylinder housing 20 defines passage 28. Affixed to the upper end 27 of hydraulic cylinder housing 20 by means of bolts 29 is sealing member 30 which will be more fully described hereinafter. Tubular member 31 fluidly communicates with cylindrical chamber 23 adjacent the upper end 27 of cylinder housing 20 and may be secured to cylinder housing 20 by suitable means, as by means of flange 32. Tubular member 31 is fluidly connectible to a source of fluid under pressure. Cylindrical chamber 23, adjacent the lower end 50 of cylinder housing 20, is vented through port 51. Preferably, however, cylindrical chamber 23, adjacent lower end 50, is fluidly connected with a surge tank 52 by means of conduit 53.

Piston 33 is arranged slidably within cylindrical chamber 23 and carries on its outer periphery sealing means 34, which may suitably be an O-ring or piston ring, adapted to prevent the passage of fluid between the said piston and the walls of cylinder housing 20 which define cylindrical chamber 23. Mechanically connected to the upper side 35 of piston 33 is flexible piston rod 36. Also mechanically affixed to the upper side 35 of piston 33 is longitudinally-split tubular sealing member 37, tubular sealing member 37 being arranged coaxially with flexible piston rod 36 and circumscribing that portion of said rod positioned within cylindrical chamber 23 and sealing member 30. Longitudinally-split tubular sealing member 37 may suitably be of any material which will circumscribe that portion of piston rod 36 positioned within cylindrical chamber 23 and sealing member 30 and which will provide a fluid-tight seal between piston rod 36 and sealing member 30. Longitudinally-split tubular sealing member 37 will ordinarily consist of natural or synthetic rubber but may suitably be of any material which will normally assume a tubular form to provide a fluid-tight seal between piston rod 36 and sealing member 30 but which is capable of assuming a flat ribbon-like configuration when rolled upon a flat surface.

In the drawing flexible piston rod 36 is shown at attached at one end to the upper side 35 of piston 33 and as passing through opening 28 and sealing member 30 and over the top of sheave 15, its other end being mechanically connected to a suitable load gripping means 38. As mentioned before, longitudinally-split tubular sealing member 37 is arranged coaxially with flexible piston rod 36 while the said rod is confined within cylindrical chamber 23 and sealing member 30 and in the drawing is shown as separating from piston rod 36 above sealing member 30 and thereafter passing over the top of guide wheel 18 and onto reel 19 upon which it is wound. As longitudinally-split tubular sealing member 37 passes over the top of guide wheel 18 it assumes a ribbon-like shape and main-

tains its ribbon-like shape while wound on reel 19.

Sealing member 30 consists of a stuffing box 39, which is affixed to the upper end 27 of cylinder housing 20 by means of bolts 29, compressible packing material 40, and plug 41. Plug 41 is adapted to fit slidably within stuffing box 39 and is secured to stuffing box 39 by means of bolts 42, the tightening of said bolts causing compression of packing material 40 to form a fluid-tight seal around longitudinally-split tubular sealing member 37.

In operation load gripping means 38 and any load attached thereto may be raised vertically by supplying fluid under pressure to cylindrical chamber 23 through tubular member 31. The fluid so introduced exerts pressure against the upper side 35 of piston 33, forcing piston 33 downwardly within cylindrical chamber 23. Flexible piston rod 36 and longitudinally-split tubular sealing member 37 also move downwardly in cooperation with piston 33. As piston rod 36 moves downwardly it also travels over the top of sheave 15 thereby raising load gripping means 38 together with the load attached thereto. As longitudinally-split tubular sealing member 37 moves downwardly in cooperation with piston 33, it unwinds from reel 19, travels over the top of guide wheel 18 and engages with piston rod 36 above sealing member 30, arranging itself coaxially with said piston rod. Sealing member 30 forces longitudinally-split tubular sealing member 37 into fluid-tight contact with piston rod 36, while packing material 40 provides a fluid-tight seal between the outer surface of longitudinally-split tubular sealing member 37 and the upper end 27 of cylinder housing 20. By arranging the parts as hereinbefore described the escape of fluid around flexible piston rod 36 as it passes in and out of cylinder housing 20 is prevented.

Ordinarily, it will be desirable to maintain fluid in the lower portion of chamber 23 below piston 33 and in surge tank 52 and conduit 53. This fluid must, of course, be under a much lower pressure than the fluid in chamber 23 above piston 33. When piston 33 is forced downwardly in chamber 23, the fluid below the piston flows through conduit 53 into surge tank 52 and when piston 33 moves upwardly in chamber 23, this fluid flows from surge tank 52 through conduit 53 into the space in chamber 23 below piston 33. The purpose in employing a surge tank is to reduce the amount of grit and dirt which would enter chamber 23 if the lower portion of the chamber were merely vented to the atmosphere. Furthermore, when fluid is maintained on both sides of piston 33, sealing member 34 is wetted from both sides and is thus more likely to provide a fluid tight seal.

When it is desired to lower load gripping member 38, together with its attached load, hydraulic fluid is permitted to escape from the space in cylindrical chamber 23 above piston 33 through tubular member 31. The rate of escape of hydraulic fluid from cylindrical chamber 23 may be controlled by throttling tubular member 31 in any suitable manner as by means of a valve, not shown. By controlling the rate of escape of fluid from cylindrical chamber 23, the rate of descent of load gripping means 38 is also controlled. As fluid escapes from cylindrical chamber 23 through tubular member 31, piston 33 moves upwardly within cylindrical chamber 23, flexible piston rod 36 and longitudinally-split

tubular sealing member 37 also moving upwardly in cooperation with piston 33. As flexible piston rod 36 and longitudinally-split tubular sealing member 37 clear sealing member 30 in their upward travel, they separate from each other, as shown most clearly in Fig. 3. Flexible piston rod 36 travels over the top of sheave 15 and longitudinally-split tubular sealing member 37 travels over the top of guide wheel 18 and onto reel 19. Reel 19 is provided with a suitable means, as for example a spiral spring 17', for causing it to tend to rotate in one direction so as to maintain tension on longitudinally-split tubular sealing member 37 so that member 37 will retain its ribbon-like configuration while wound on reel 19.

Flexible piston rod 36 must be of sufficient strength to act as a piston rod in tension when lifting or suspending the loads engaged by load gripping means 38. It must also be sufficiently flexible to travel over the top of sheave 15 without acquiring any appreciable permanent distortion or set. The outer surface of flexible piston rod 36 must be sufficiently uniform so that when it is circumscribed by longitudinally-split tubular sealing member 37, its outer surface will cooperate with the inner surface of member 37 to form a fluid-tight seal between the two surfaces while permitting the outer surface of longitudinally-split tubular sealing member 37 to maintain a fluid-tight seal when passing through sealing member 30. Although any type of flexible line which will meet the aforementioned conditions may satisfactorily be employed, I prefer to employ a flexible wire line of any of the types conventionally employed in hoisting equipment.

Figs. 4 and 5 illustrate a modification of the embodiment shown in Figs. 1 and 2. In this modification, sealing member 30 and guide wheel 18 of the embodiment shown in Figs. 1 and 2 are eliminated. Referring to Figs. 4 and 5, 10 designates a supporting structure, such as a derrick, and 11 designates a transverse member forming a part of the upper portion of supporting structure 10. Hydraulic cylinder housing 20 defining cylindrical chamber 23 is supported in an upright position from supporting member 10 and may suitably be affixed to transverse member 11 by bolts 24. The upper end 27 of hydraulic cylinder housing 20 defines passage 28. Upright journaling members 12 affixed to transverse member 11 support axle 14 on which is mounted sheave 15 for rotation about its axis. Journals 12 and, accordingly, sheave 15 are so arranged above cylindrical housing 20 that the outer periphery 25 of sheave 15 is substantially tangential to the longitudinal axis of cylindrical housing 20.

Pivoting members 60 mounted on pivot member 61, secured to transverse member 11, tend to support axle 62 on which is mounted reel 63 for rotation thereon. Spring 64 is secured by one end to member 60 and the other end to the top of cylindrical housing member 20, and tends to bias pivoting members 60 toward cylindrical housing member 20.

Piston 33 with sealing member 34 on its outer periphery is disposed within chamber 23. One end of flexible piston rod 36 and one end of longitudinally-split tubular sealing member 37 are affixed to piston 33, while the other end of flexible piston rod 36 passes over the top of sheave 15 and the other end of longitudinally-split tubular sealing member 37 is wound onto reel 63. That por-

tion of flexible piston rod 36 and longitudinally-split tubular sealing member 37 positioned within chamber 23 and port 28 are in coaxial relation. However, as piston rod 36 and member 37 pass through port 28, they separate from each other as shown. Inasmuch as pivoting members 60 and, accordingly, reel 63 are biased toward cylindrical housing member 20 by means of spring 64, the outer periphery 65 of reel 63 is always maintained substantially tangential to the longitudinal axis of cylindrical housing member 20. Of course, as longitudinally-split tubular sealing member 37 winds onto reel 63 on upward movement of piston 33, pivoting members 60 and reel 63 tend to move away from housing 20 against the tension of spring 64.

Inasmuch as the stuffing box of Figs. 1 and 2 is eliminated from the modification shown in Figs. 3 and 4, it is necessary in the modification shown in Figs. 3 and 4 that port 28 be of the proper dimensions to force longitudinally-split tubular sealing member 37 into sufficiently close contact with flexible piston rod 36 to cause said member 37 to provide a fluid-tight seal around said piston rod.

While the embodiment of the hoisting device of my invention shown in Figs. 1 to 5, inclusive, utilizes only one hydraulic cylinder unit including the cylinder housing, piston, piston rod, longitudinally-split tubular sealing member, sheave, and reel, the hoisting device of my invention may comprise a plurality of such hydraulic cylinder units. Of course, the total number of such units employed in any particular instance will depend upon the individual lifting potential of each unit and upon the magnitude of the load to be lifted. It will be appreciated that various modifications may be made in the various units themselves when a plurality are employed in order to accommodate the units to the supporting structure and to integrate the units into an efficient working assembly. It will also be appreciated that the supporting structure may need to be suitably modified to receive a plurality of hydraulic cylinder units. Portions of the hydraulic cylinder unit may even be incorporated in the supporting structure itself to form a part thereof. For example, one or more legs of a supporting structure, such as a drilling derrick, may be replaced by a hydraulic cylinder housing of a hydraulic cylinder unit which, in effect, will make the hydraulic cylinder housing a leg of the derrick. Various other adaptations will, of course, become obvious as further embodiments of my invention are hereinafter described.

In Figs. 6 and 7 an embodiment is shown in which four cylinder units are employed. Turning now to Figs. 6 and 7, 100 designates a supporting structure, such as a derrick, on which the device of my invention may be mounted. Numeral 101 designates a transverse member forming a part of the upper portion of supporting structure 100, transverse member 101 defining opening 102 therein. A plurality of platform members 104 extend laterally from supporting structure 100, the said platform members being supported by suitable bracing members 105. Mounted on each of the platform members 104 are upright journaling members 106 and 106', and upright journaling members 107 and 107', journaling members 106 and 106' being adapted to receive and support axle 108 for rotation about its axis and journaling members 107 and 107' being adapted to receive and support axle 109 for

rotation about its axis. Guide wheel 110 is mounted on axle 109 for rotation therewith and reel 111 is mounted on axle 108 for rotation therewith.

A plurality of journaling members 112 and 112' are mounted on the transverse member 101, members 112 and 112' being adapted to receive and support axle 113 for rotation about its axis. A sheave 114 is mounted on each of axles 113 for rotation therewith. Fig. 7 shows that one sheave 114, one guide wheel 110, and one reel 111 are arranged in a group, there being a total of four such groups. Within each group, axles 108, 109, and 113 are substantially parallel to each other. Each of sheaves 114 are arranged so that one edge 115 of each of said sheaves is located above opening 102 in transverse member 101.

Hydraulic cylinder housing member 116 is shown in Fig. 6 as being affixed to leg 117 of supporting structure 100. It will be understood that rather than being affixed to leg 117, leg 117 may be dispensed with entirely, hydraulic cylinder housing member 116 replacing same and forming a part of supporting structure 100.

Hydraulic cylinder housing member 116 defines internal cylindrical chamber 118, tubular member 119 fluidly communicating with internal chamber 118 adjacent the upper end 120 of cylinder housing member 116. Affixed to the upper end 120 of hydraulic cylinder housing member 116 as by means of bolts 121 is sealing member 122. Sealing member 122 may be identical in construction with sealing member 30 shown in Fig. 1, the details of which have been hereinbefore described, or it may be similar to the structure shown in Fig. 4 and hereinbefore described.

Piston 123 is slidably arranged within cylindrical chamber 118 and carries on its outer periphery sealing means 124, which may suitably be an O-ring or piston ring, adapted to prevent the passage of fluid between said piston and the interior walls of cylindrical housing member 116. Mechanically connected to the upper side 125 of piston 123 is flexible piston rod 126. Also affixed to the upper end 125 of piston 123 is longitudinally-split tubular sealing member 137, tubular sealing member 137 being arranged coaxially with flexible piston rod 126 and circumscribing that portion of said rod positioned within cylindrical chamber 118 and sealing member 122. Flexible piston rod 126 passes over the top of sheave 114, the free end of said rod being attached to load engaging member 128. Longitudinally-split tubular sealing member 137 separates from flexible piston rod 126 on emerging from sealing member 122 and passes over the top of guide wheel 110 and onto reel 111.

Hydraulic cylinder housing member 116, sheave 114, and guide wheel 110 are so arranged with respect to each other that periphery 130 of sheave 114 and periphery 131 of guide wheel 110 are substantially tangential to the longitudinal axis of hydraulic cylinder housing member 116. This arrangement is necessary so that flexible piston rod 126 may readily pass over the top of sheave 114 while longitudinally-split tubular sealing member 137 may properly separate from piston rod 126 to pass over the top of guide wheel 110 and onto reel 111.

Since the operation of each of the individual hydraulic cylinder units shown in Figs. 6 and 7 is identical with the operation of the hydraulic cylinder unit shown in Fig. 1, its operation will not again be described in detail. It will be sufficient to state that all of the hydraulic cylinder

units may be simultaneously supplied with hydraulic fluid to actuate all of them simultaneously, or it may be desirable in some instances to supply hydraulic fluid to less than all. In this last-mentioned instance the units not actually being supplied with hydraulic fluid will go through their normal cycle but without accomplishing any useful work. Of course, it will be understood that one or more of the hydraulic cylinder units may be taken out of service while the remainder are required to perform the required hoisting service by the simple expedient of disconnecting flexible piston rod 126 from load engaging member 128.

In the description of Figs. 1 to 7 hereinbefore given, the sealing member employed for providing a seal between flexible piston rod 36 and the upper end 27 of hydraulic cylinder housing 20 has been designated by numeral 37 and has been described as a longitudinally split, resilient, normally tubular sealing member. It will be understood, however, that the resilient sealing member adapted to pass through port 28 in the upper end 27 of cylindrical housing member 20 need not necessarily be normally tubular in form but may normally be ribbon-like in form as shown in Fig. 8. In Fig. 8 the sealing member 37' adapted to move longitudinally through port 28 defined in the upper end 27 of hydraulic cylinder housing 20 in cooperation with flexible piston rod 36 to provide a fluid-tight seal between flexible piston rod 36 and upper end 27 normally possesses a flat ribbon-like configuration and only assumes a tubular configuration when it circumscribes flexible piston rod 36 as the said rod passes through port 28. Resilient sealing member 37' is of such a width that as it passes through port 28 in cooperation with flexible piston rod 36, it arranges itself coaxially around piston rod 36, the outer edges 150 and 150' meeting, as at 151, to completely circumscribe flexible piston rod 36 without any substantial gap between edges 150 and 150' and without any substantial overlapping of said edges. Inasmuch as resilient sealing member 37' normally possesses a ribbon-like configuration, that portion of member 37' not actually confined within port 28 around flexible piston rod 36 will normally possess this ribbon-like configuration as shown clearly in Fig. 8. Resilient sealing member 37' will ordinarily consist of natural or synthetic rubber but may suitably be of any resilient material normally having a flat ribbon-like configuration but which is capable of assuming a tubular configuration when passed through a restricted opening, as for example when passed through port 28. It will further be understood, of course, that resilient sealing member 37' may be used in any of the embodiments or modifications shown in Figs. 1 to 7, inclusive, in place of the longitudinally split, resilient, normally tubular sealing member 37.

What I wish to claim as new and useful and to secure by Letters Patent is:

1. A hydraulic hoisting device comprising, in combination, a housing having walls defining a chamber and a port communicating with said chamber, the axis of said port being substantially coincident with the longitudinal axis of said chamber, said chamber being fluidly connectible with a source of fluid under pressure, a piston slidably arranged in said chamber for longitudinal movement therein in fluid-tight relation with the walls forming said chamber, a rotatable sheave mounted in spaced relation from said housing, the outer periphery of said sheave being

substantially tangential to the longitudinal axis of said chamber, a flexible piston rod affixed at one end to said piston and extending through said port and over said sheave, a resilient sealing member adapted to move longitudinally through said port in cooperation with said flexible piston rod to provide a fluid-tight seal between said flexible piston rod and the walls of said housing defining said port, and a reel mounted in spaced relation from said housing for receiving in the form of an elongated strip the resilient sealing member when said piston moves toward the piston rod end of said chamber and for paying off said resilient sealing member when said piston is moving away from the piston rod end of said chamber.

2. A hydraulic hoisting device comprising, in combination, at least one housing having walls defining at least one chamber and a port communicating with said at least one chamber, the axis of said port being substantially coincident with the longitudinal axis of said at least one chamber, the said at least one chamber being fluidly connectible with a source of fluid under pressure, a piston slidably arranged in said at least one chamber for longitudinal movement therein in fluid-tight relation with the walls forming said at least one chamber, a rotatable sheave for each said at least one chamber mounted in spaced relation from said housing, the outer periphery of said sheave being substantially tangential to the longitudinal axis of said chamber, a flexible piston rod affixed at one end to said piston and extending through said port and over said sheave, a resilient sealing member adapted to move longitudinally through said port in cooperation with said flexible piston rod to provide a fluid-tight seal between said flexible piston rod and the walls of said housing defining said port, and a reel mounted in spaced relation from said housing for receiving in the form of an elongated strip the resilient sealing member when said piston moves toward the piston rod end of said chamber and for paying off said resilient sealing member when said piston is moving away from the piston rod end of said chamber.

3. A hydraulic hoisting device comprising, in combination, a housing having walls defining a chamber and a port communicating with said chamber, said chamber being fluidly connectible with a source of fluid under pressure, a piston slidably arranged in said chamber for longitudinal movement therein in fluid-tight relation with the housing walls forming said chamber, a flexi-

ble piston rod affixed at one end to said piston and extending through said port, the other end of said rod being adapted to engage with a load for hoisting said load, a longitudinally-split, resilient, normally tubular sealing member arranged coaxially with that portion of the flexible piston rod positioned within said chamber and said port and adapted to provide a fluid-tight seal between said flexible piston rod and the walls of said housing defining said port, and a reel mounted in spaced relation from said housing for receiving in the form of an elongated strip said longitudinally split, resilient, normally tubular sealing member when said piston moves toward the piston rod end of said chamber and for paying off said sealing member when said piston is moving away from the piston rod end of said chamber.

4. A hydraulic hoisting device comprising, in combination, at least one housing having walls defining at least one chamber and a port communicating with said at least one chamber, said at least one chamber being fluidly connectible with a source of fluid under pressure, a piston slidably arranged in said at least one chamber for longitudinal movement therein in fluid-tight relation with the housing walls forming said chamber, a flexible piston rod affixed at one end to said piston and extending through said port, the other end of said rod being adapted to engage with a load for hoisting said load, a longitudinally-split, resilient, normally tubular sealing member arranged coaxially with that portion of the flexible piston rod positioned within said at least one chamber and said port and adapted to provide a fluid-tight seal between said flexible piston rod and the walls of said housing defining said port, and a reel mounted in spaced relation from said housing for receiving in the form of an elongated strip the longitudinally split, resilient, normally tubular sealing member when said piston moves toward the piston rod end of said chamber and for paying off said sealing member when said piston is moving away from the piston rod end of said chamber.
